UNITED STATES PATENT OFFICE.

JOHN B. KENISON, OF LYNN, MASSACHUSETTS, ASSIGNOR TO THE AMERICAN CAR SPRINKLER COMPANY, OF WORCESTER, MASSACHUSETTS.

SPRINKLER-CAR.

SPECIFICATION forming part of Letters Patent No. 633,597, dated September 26, 1899.

Application filed November 15, 1898. Serial No. 696,529. (No model.)

To all whom it may concern:

Be it known that I, JOHN B. KENISON, a citizen of the United States, residing at Lynn, in the county of Essex and State of Massachusetts, have invented a new and useful Sprinkler-Car, of which the following is a specification.

My invention relates to that class of sprinkler-cars which are designed not only for sprinkling the space between the tracks upon which the cars run, but also for sprinkling or wetting down the roadway at one or both sides of such track.

The objects of my present invention are to provide a simple and efficient construction for forcing the water through the sprinkling devices of the car under a constant pressure and to provide the sprinkler-car with simple and efficient side sprinklers which can be easily adjusted to throw water to different distances from the sides of the car, so as to sprinkle streets of various widths.

To these ends my invention consists of the parts and combinations of parts, as hereinafter described, and more particularly pointed out in the claims at the end of this specification.

In the accompanying two sheets of drawings, Figure 1 is a sectional view of a sprinkler-car constructed according to my invention. Fig. 2 is an end view of the same partially in section, and Fig. 3 is an enlarged sectional view of the regulator which I may employ for automatically controlling the motor which drives the pump.

Sprinkler-cars constructed according to my present invention have been especially designed for use on the ordinary electric street-railways, and when thus used a sprinkler-car constructed according to my invention comprises a car-body, a closed tank carried thereby, a pump, an electric motor for actuating the pump, and an automatic regulator for starting and stopping the motor, so as to maintain a constant pressure in the tank.

The electric motor for actuating the pump may be included in a shunt-circuit from the trolley, and by providing means for automatically controlling the motor the same will be driven so as to maintain the desired pressure

in the tank without requiring any attention or adjustment from the operators running the car.

The motor may be automatically controlled by various forms of regulators; but in practice I preferably employ a movable rheostat-arm which is connected to be actuated by a flexible diaphragm, so as to throw in or cut out suitable resistance-coils when the motor is to be stopped or started. A spring is preferably combined with the rheostat-arm, so as to normally hold the same in position to stop the motor or to drive the same at full speed and to prevent movement of the rheostat-arm under comparatively slight variations of pressure.

The spraying or sprinkling devices which I employ may be of any of the ordinary or preferred constructions; but in practice I preferably provide the sprinkler-cars constructed according to my invention with perforated vertical pipes substantially at each corner of the car-body.

In practice I have found that the use of uniformly-perforated sprinkler-pipes does not insure a uniform sprinkling over the entire surface which is being wet down—that is to say, the water which is delivered near the upper ends of the sprinkler-pipes has to travel a greater distance from the tank, and as the pressure at the upper end of the sprinkler-pipes is somewhat diminished by the fact that a portion of the flow or stream is diverted through the perforations along the length of the pipe the supply of water delivered near the upper end of the vertical sprinkler-pipes is apt to be less than that delivered from the perforations near the lower ends of the vertical sprinkler-pipes. To overcome this defect and insure a uniform sprinkling of the roadways at the sides of the track, I propose to arrange or graduate the perforations in the vertical sprinkler-pipes, so that the upper ends of said vertical sprinkler-pipes will be more openly perforated than the lower ends thereof. This arranging or graduating of perforations in the sprinkler-pipes may be accomplished either by graduating the bore or diameters of the perforations, employing larger perforations near the top of the pipe,

or by arranging perforations more closely together near the top of the pipe than near the bottom thereof.

In order to enable sprinkler-cars constructed according to my invention to be used with advantage under varying conditions—that is to say, to sprinkle roadways or streets of different widths—I preferably combine the perforated vertical sprinkler-pipes with means for shutting off a greater or less part thereof, so that water will be thrown to any desired distance from the sides of the car. To accomplish this purpose, I preferably employ sleeves which fit telescopically onto the vertical sprinkler-pipes and which are connected by links to suitable levers, whereby said sleeves may be moved up and down to secure the desired adjustment.

Referring to the drawings and in detail, A 20 designates a car-body of any desired or preferred construction. Mounted or carried in the car-body A is a closed tank B. A perforated vertical sprinkler-pipe 10 is preferably located at each corner of the car-body, 25 and said sprinkler-pipes 10 are connected to the tank B by pipes 11. The vertical sprinkler-pipes 10, as shown most clearly in Figs. 1 and 2, are perforated somewhat more openly near their upper ends than at their lower ends, 30 so as to insure an even distribution of water from the curbing to the track upon which the car runs. Shut-off valves 12 are located in the inlet-pipes 11 and may be operated from the platforms of the car by means of handles 35 14 and operating-levers 13, which are connected by suitable links to turn the inlet-valves 12, as shown. Telescopically mounted on the upright sprinkler-pipes 10 are sleeves 15, which are connected by links 16 to adjusting-levers 17. The adjusting-levers 17 40 may be pinned or fixed in any desired position, as shown in Fig. 2.

To maintain pressure in the tank B, I preferably employ an air-pump P, which may be 45 mounted on top of the tank and actuated from an electric motor M.

The electric motor M is preferably controlled by or started and stopped by an automatic regulator, as R.

50 The crank-shaft of the pump P, as illustrated, is driven from the motor M by means of a worm and worm-wheel connected as at 19.

A trolley-arm C is mounted on top of the car A in the ordinary manner, and leading down from the trolley-arm C is a wire a, which forms part of a shunt-circuit including the motor M.

The regulator which I preferably employ for automatically controlling the motor is 60 most clearly illustrated in Fig. 3. As shown in this figure, the regulator comprises a diaphragm-casing 20, which incloses a flexible diaphragm 21, which is acted upon by the air pressure in the upper part of the tank B.

65 The flexible diaphragm 21 is connected by a valve-stem to move the rheostat-arm 22,

which is pivotally mounted in a bracket extending up from the diaphragm-casing. A weight 23 is adjustably mounted on the rheostat-arm 22, and in order to hold the rheostat-arm 22 either in its raised or lowered position, so that the same will not be affected by slight variations in pressure, I preferably provide the shaft of the rheostat-arm 22 with an upwardly-extending projection, to which 70 is connected a spring 24, which is moved to opposite sides of the pivot of the rheostat-arm as the same is moved up and down and tends to hold the rheostat-arm in either its extreme upper or lower position. Secured 75 to but insulated from the diaphragm-casing 20 is a rheostat-plate, having contact pieces or terminals for co-operating with the rheostat-arm 22. The contact pieces or terminals of the plate are connected to ordinary resistance-coils, as indicated diagrammatically by the wires p. By means of this construction it will be seen that when the pressure in the tank B exceeds the desired limit, as determined by the adjustable weight 23, the 80 rheostat-arm 22 will be raised and the resistance-coils thrown into the motor-circuit, until finally when the rheostat-arm reaches its highest position the motor-circuit will be broken and the motor stopped. When the 85 pressure in the tank B falls below the desired point, the rheostat-arm 22 will descend, and the pump-actuating motor will be started up again.

It is obvious, of course, that I may dispense 90 with the connections through a rheostat and may connect a flexible diaphragm or other pressure-controlled device, so as to make and break the motor-circuit directly; but I prefer to employ the construction herein illustrated, 95 as it has been found in practice that if the full strength of the motor-current is turned on or off the armature or other parts of the motor are apt to be injured.

When the tank B is to be filled, it is desirable 100 that the air-pressure should be exhausted therefrom, and in order to accomplish this purpose air-pipes 25 may extend to the platforms of the car, where they are provided with exhaust-valves 24, as shown in Fig. 1. 115 Extending down from opposite sides of the tank B are filling-pipes 26, having shut-off valves 27. These filling-pipes 26 at the side of the car-body may be used to advantage where the tank is to be filled from hydrants 120 or sources of water-supply at one or the other side of the track on which the car runs. If the hydrants or other source of water-supply are located between the tracks, however, I 125 preferably employ pivotally-supported centrally-located filling-pipes, as illustrated in the patent to Gathright *et al.*, No. 570,990, of November 10, 1896.

In the use of a sprinkler-car constructed according to my invention the side sprinkling devices are adjusted to throw water to the desired distance from the sides of the car,

and when passing vehicles or other obstacles the supply of water to the side sprinkler-pipes may be shut off by closing the inlet-valves 12.

I am aware that changes may be made in the construction of sprinkler-cars by those who are skilled in the art without departing from the scope of my invention as expressed in the claims. I do not wish, therefore, to be limited to the forms which I have shown and described; but

What I do claim, and desire to secure by Letters Patent of the United States, is—

1. In a sprinkler-car, the combination of a car-body A, a tank B carried thereby, a vertical sprinkler-pipe 10, a pipe 11 connecting said vertical sprinkler-pipe 10 and tank B, a shut-off valve 12, connections for actuating said shut-off valve from the car-platform, a sleeve 15 fitting onto the vertical sprinkler-pipe so as to shut off a greater or less portion of said vertical sprinkler-pipe, and an adjusting-lever 17 and connections for adjusting the sleeve from the car-platform, substantially as described.

2. In a sprinkler-car, the combination of a car-body, a tank, sprinkler-pipes connected to said tank, a pump, an electric motor for actuating the pump, and means controlled by

the pressure generated by the pump for starting and stopping the motor, substantially as described.

3. In a sprinkler-car, the combination of a car-body, a tank carried thereby, sprinkler-pipes connected to said tank, an electric motor, a rheostat-arm, and means controlled by the pressure generated by the pump for shifting the rheostat-arm to start and stop said motor, substantially as described.

4. In a sprinkler-car, the combination of a car-body, a tank carried thereby, sprinkler-pipes connected to said tank, a pump, an electric motor, a rheostat-arm, a flexible diaphragm acted upon by the pressure in the tank connected to move the said rheostat-arm, and a spring for holding the rheostat-arm at the limits of its movement against slight variations in the pressure, substantially as described.

In testimony whereof I have hereunto set my hand in the presence of two subscribing witnesses.

JOHN B. KENISON.
